HYDRAULIC PUMP ASSEMBLY

Rudolf Amsler, Neuhausen am Rheinfall, Switzerland, assignor to Schweizerische Industrie-Gesellschaft, Neuhausen am Rheinfall, Switzerland, a Swiss firm

Application February 27, 1948, Serial No. 11,769
In Switzerland February 5, 1947

Section 1, Public Law 690, August 8, 1946

6 Claims. (Cl. 103—45)

1

The invention relates to improvements in hydraulically operated pump assemblies for the delivery of a continuously adjustable quantity of liquid which, for instance, is required for the operation of feeding devices in machine tools.

It is an object of the invention to make the operation of the pump assembly independent of the condition and the temperature of the liquid, for instance oil, to be delivered.

Another object of the invention is a pump assembly which is adapted to operate against an adjustable pressure of the liquid to be delivered, the pressure of which may be higher or lower or which may be the same as the pressure of the operating liquid.

The pump unit proper—at least one is provided and the same extends parallel to and is radially spaced from the axis of a rotatable operating piston—constitutes a reciprocating hydraulic motor coupled with a pump. During the operation of the pump assembly the hydraulic motor and pump alternate their functions, that is, during movement in one direction the left side of the unit operates as a motor and the right side operates as a pump, while during the movement in the opposite direction the functions of the sides of the unit are reversed.

Still another object of the invention is to vary the amount of the delivery of the liquid by changing the stroke of the piston of the pump unit by inserting a pin into the housing, one for each pump unit so as to limit the reciprocating movement of the piston of the same. There will be provided as many pins as there are pump units in the assembly.

Another object of the invention is to operate the pump unit, or pump units as the case may be, by an operating medium which is furnished by another pump which latter is arranged in the before mentioned rotatable operating piston. The latter is rotatably mounted in a casing in the wall of which are arranged longitudinal bores, one for each pump unit, each bore forming a cylinder for one of said pump units.

It is also an object of the invention to improve the volumetric efficiency of the pump assembly by operating both the drive end and the delivery end of the pump assembly with the same pressure.

Other objects of the invention will be apparent or will be specifically pointed out in the description forming a part of this specification, but it is to be understood that the invention is not limited to the embodiments described in this description, as various forms may be adopted within the scope of the claims.

2

Referring to the drawing:

Fig. 1 is a longitudinal sectional view of a pump assembly in accordance with the invention,

Fig. 2 is another longitudinal sectional view of the pump assembly substantially along the angular line C—C of Fig. 4,

Fig. 3 is a cross sectional view of the pump assembly substantially along the line A—A of Fig. 1,

Fig. 4 is a cross sectional view of the pump assembly along the line B—B of Fig. 2,

Fig. 5 is a longitudinal cross sectional view of a modification of a pump assembly according to the present invention,

15 Fig. 6 is a similar longitudinal cross sectional view as shown in Fig. 5, except that the rotary piston is in another position and that the pistons of the pump unit have been shifted to another position, and

20 Figure 7 is a cross sectional view of the pump assembly substantially along the line D—D of Fig. 5.

Referring to the drawings, particularly Fig. 1, the pump assembly consists of three principal parts, namely the drive shaft A with the operating piston 1 thereon, the cylindrical casing B and the adjusting device C. The operating piston 1 and the shaft A rotate as a unit and are driven by a motor, not shown. Within the operating

25 piston 1 is arranged a pump 2 which in the embodiment shown comprises a screw pump consisting of a center screw 2^a and two lateral screws 37 which have a smaller diameter than the center screw 2^a. The two screws 37 are rotatably supported in the operating piston 1 and when the latter is rotated the two lateral screws 37 are caused to roll about the center screw 2^a, since the thread of the screws 37 engages the thread of the screw 2^a. The center screw 2^a is provided

30 with an outwardly projecting threaded portion 2^b which projects through the cover 36 of the casing B and has attached thereto a nut which secures the center screw 2^a fixedly to the cover 36.

35 When the operating piston 1 is rotated in the manner described, the operating fluid entering the ports or slots 3 at one end of the casing B travels along the center screw 2^a and is forced into the chamber 4 at the other end of the casing B. A conduit 5 connects the chamber 4 with the device to be operated by the liquid.

40 The operating piston 1 is also provided with two longitudinal passages 6 and 7 which extend parallel to the axis of the screw 2^a and are continuously in communication with the chamber 4. 45 In the position of the operating piston 1 as shown

in Fig. 1 the operating fluid is conducted by the passage 6 and the ports 8 and 9 into the right end of the cylinder 10 formed by a portion of a longitudinal bore arranged in the wall of the casing and extending parallel to the axis of the operating piston 1. The left end of the cylinder 10 is in communication with the port 11, the passage 12, the annular passage 13 and the port 14 which latter discharges the liquid from the pump assembly. Furthermore, the passage 6 by means of the ports 15 and 16 conducts operating liquid to the right end of the cylinder 17 which is formed by another portion of the cylindrical bore arranged in the wall of the casing B. The left end of the cylinder 17 is connected by the port 18, the passage 19 and the annular passage 20 with a conduit 21 which conducts the operating liquid to the devices to be operated. The longitudinal bore forming the axially aligned cylinders 10 and 17 has mounted therein three axially aligned but separated pistons 22, 23 and 24 all of which move toward the left so that the operating liquid in the left end of the cylinder 17 is forced toward the device to be operated. This movement of the pistons 22, 23 and 24 takes place by the operating liquid entering the right end of the cylinder 10. The piston 22 in this instance functions as motor piston while the piston 24 in the cylinder 17 functions as pump piston.

Upon rotation of the operating piston 1 about an angle of 180°, which position is illustrated in Fig. 2, the just described operation of the pump unit is reversed. The operating liquid is now conducted by the passage 7 into the ports 25 and 18 and into the left side of the cylinder 17 and the piston 24 therein acts as motor piston and moves the other pistons 23 and 22 toward the right. The right end of the cylinder 17 by means of the port 16, the passage 26 and the annular passage 13 is connected with the discharge port 14. Furthermore, the passage 7 conducts operating liquid by means of the ports 26' and 11 into the left end of the cylinder 10; and into the right end of the cylinder 10 by means of the port 9, the passage 27, the annular passage 28 and the passage 29 is connected with the line 21 which conducts the operating liquid to the device to be operated. The pistons 22, 23 and 24 move toward the right and the operating liquid in the right end of the cylinder 10 is thereby forced into passages 9, 27, 28, 29 and 21 which lead to the device to be operated.

The adjustment of the quantity of liquid to be delivered is affected by the longitudinally slideable pin 30 which extends into the outer end of the bore forming the cylinders 10 and 17. A manually rotatable hand wheel 31 is in threaded engagement with the outer end 2^b of the central screw 2^a and has an annular flange which engages the outer end of the pin 30 as shown in Figs. 1 and 2. In case that the pump assembly is provided with a plurality of pump units 10, 17, 22, 23 and 24 there are provided a corresponding number of pins 30, but all of these pins are simultaneously adjusted by a single hand wheel 31. If desired, the manually operable adjusting device may also be hydraulically adjusted.

In order to assure that the pressure of the operating liquid will be the same as the pressure of the delivered liquid, that is, the liquid which is conducted to the devices to be operated, it is advisable to conduct the liquid delivered by the pump unit or units, for instance the liquid in the line 21, to the right side of an equalizer or

adjusting piston 32 as shown in Fig. 1. From the right side of the chamber in which the piston 32 is slidably mounted, a line 33 leads to the devices to be operated. The left side of the chamber in which the piston 32 is arranged is in communication with the pressure chamber 4 in the casing B. The arrangement is such that the piston 32 is automatically adjusted to such a position that the pressure in the line 5 will be the same as the pressure in the line 33. 34 is a stop which limits the movement of the piston 22 toward the right and 35 designates the other cover of the cylindrical casing B.

If the pump assembly has to deliver another medium other than that of the operating medium, a condition which, for instance, may arise in the chemical industry, then this condition can easily be met by the pump assembly of the present invention. It is only necessary to connect the outer ends of the cylinders 10 and 17, which in the above identified embodiment are brought into communication with the devices to be operated by the liquid, in communication with the discharge ports. Fig. 5 illustrates by way of example in a longitudinal sectional view such a modified pump assembly and Fig. 6 illustrates in a partial sectional view this modification after the operating piston has been rotated about an angle of 180° from its position shown in Fig. 5. The passage 14, which by means of the annular passage 13, the passages 12 and 26 and the ports 11 and 16 is connected with the inner ends of the cylinders 10 and 17 leads to the devices to be operated. The liquid is admitted to the cylinders 10 and 17 by means of the ports 11, 16, 40 and 41, the passage 42, the annular passage 43 and the supply conduit 44. The operation of the pump assembly is the same as already described.

What I claim as my invention is:

40 1. A hydraulic pump assembly comprising a casing closed at both ends and having mounted therein a rotatable operating piston, pump means within said operating piston and operable upon rotation of said operating piston to convey liquid from an inlet at one end of said casing to an outlet at the other end of said casing, the wall of said casing having a bore therein extending parallel to the axis of rotation of said operating piston and means at opposite ends of said casing 45 wall forming a supply port and a delivery conduit respectively, a discharge conduit between the ends of said casing, and a piston assembly consisting of at least three axially aligned separate parts mounted for reciprocative movement in said bore, said operating piston and said casing being each provided with passages and ports adapted to connect said other end of the casing with said bore in a manner that said separate parts of the piston assembly, upon rotation of said operating 50 piston, are actuated to function alternately as pump piston and motor piston to deliver and expel fluid into said delivery conduit and discharge conduit respectively.

65 2. A hydraulic pump assembly comprising a casing closed at both ends and having mounted therein a rotatable operating piston, pump means within said operating piston and operable upon rotation of said operating piston to convey an operating liquid from an inlet at one end of said 70 casing to an outlet at the other end of said casing, the wall of said casing having a bore therein extending parallel to the axis of rotation of said operating piston and means at opposite ends of said casing wall forming a supply port and a delivery conduit respectively, a discharge conduit

between the ends of said casing, and a piston assembly consisting of at least three axially aligned separate parts mounted for reciprocative movement in said bore, said operating piston and said casing being each provided with passages and ports adapted to connect said supply port, delivery conduit and discharge conduit with said bore in a manner that said separate parts of the piston assembly, upon rotation of said operating piston, are actuated to function alternately as pump piston and motor piston to deliver and expel another fluid into said delivery conduit and discharge conduit respectively.

3. A hydraulic pump assembly comprising a casing closed at both ends and having mounted therein a rotatable operating piston, pump means within said operating piston and operable upon rotation of said operating piston to convey liquid from an inlet at one end of said casing to an outlet at the other end of said casing, the wall of said casing having a bore therein extending parallel to the axis of rotation of said operating piston and means at opposite ends of said casing wall forming a supply port and a delivery conduit respectively, a discharge conduit between the ends of said casing, a piston assembly consisting of at least three axially aligned separate parts mounted for reciprocative movement in said bore, said operating piston and said casing being each provided with passages and ports adapted to connect said other end of the casing with said bore in a manner that said separate parts of the piston assembly, upon rotation of said operating piston, are actuated to function alternately as pump piston and motor piston to deliver and expel fluid into said delivery conduit and discharge conduit respectively, and means for gradually varying the stroke of the reciprocating piston assembly.

4. A hydraulic pump as claimed in claim 1, in which the pump means in said operating piston consists of a screw pump the main axis of which is coincident with the axis of rotation of said operating piston.

5. A hydraulic pump assembly comprising a casing closed at both ends and having mounted therein a rotatable operating piston, pump means within said operating piston and operable upon rotation of said operating piston to convey liquid from an inlet at one end of said casing to an

outlet at the other end of said casing, the wall of said casing having a bore therein extending parallel to the axis of rotation of said operating piston and means at opposite ends of said casing wall forming a supply port and a delivery conduit respectively, a discharge conduit between the ends of said casing, a piston assembly consisting of at least three axially aligned separate parts mounted for reciprocative movement in said bore, said operating piston and said casing being each provided with passages and ports adapted to connect said other end of the casing with said bore in a manner that said separate parts of the piston assembly, upon rotation of said operating piston, are actuated to function alternately as pump piston and motor piston to deliver and expel fluid into said delivery conduit and discharge conduit respectively, and means for gradually varying the stroke of the reciprocating piston assembly.

6. A hydraulic pump assembly comprising a casing closed at both ends and having mounted therein a rotatable operating piston, pump means within said operating piston and operable upon rotation of said operating piston to convey liquid from an inlet at one end of said casing to an outlet at the other end of said casing, the wall of said casing having a bore therein extending parallel to the axis of rotation of said operating piston and means at opposite ends of said casing wall forming a supply port and a delivery conduit respectively, a discharge conduit between the ends of said casing, a piston assembly consisting of at least three axially aligned separate parts mounted for reciprocative movement in said bore, said operating piston and said casing being each provided with passages and ports adapted to connect said other end of the casing with said bore in a manner that said separate parts of the piston assembly, upon rotation of said operating piston, are actuated to function alternately as pump piston and motor piston to deliver and expel fluid into said delivery conduit and discharge conduit respectively, and pressure regulating means for automatically equalizing the pressure of the liquid in said other end of the casing and in said delivery conduit.

45 7. A hydraulic pump assembly comprising a casing closed at both ends and having mounted therein a rotatable operating piston, pump means within said operating piston and operable upon rotation of said operating piston to convey liquid from an inlet at one end of said casing to an
